(57) **CLAIM**

The ornamental design for a hand-held cradle head camera, as shown and described.

DESCRIPTION

FIG. 1 is a rear and top perspective view of a hand-held cradle head camera, showing our new design;

FIG. 2 is a front and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric **9** in FIG. 1;

FIG. 10 is an enlarged view of a portion indicated with numeric **10** in FIG. 2; and,

FIG. 11 is an enlarged view of a portion indicated with numeric **11** in FIG. 2.

The broken lines shown in the drawings are included for the purpose of illustrating unclaimed portions of hand held cradle head camera and forms no part of the claimed design. The dash dot dash lines in FIGS. 1, 2, 9, 10 and 11 are shown for the purpose of depicting areas of enlargement and form no part of the claimed design.

1 Claim, 11 Drawing Sheets
